UNITED STATES PATENT OFFICE.

HENRY F. JAMES, OF FRANKLIN, PENNSYLVANIA.

COMBINATION GIN AND TRANSPORT.

No. 892,733.

Specification of Letters Patent.

Patented July 7, 1908.

Application filed February 24, 1906. Serial No. 302,779.

To all whom it may concern:

Be it known that I, HENRY F. JAMES, citizen of the United States, residing at Franklin, in the county of Venango and State of Pennsylvania, have invented certain new and useful Improvements in a Combination Gin and Transport, of which the following is a specification, reference being had therein to the accompanying drawing.

10 My invention relates to an improved combination gin and transport, the object, construction and operation of which is fully set forth in the following specification, reference being had to the accompanying drawings, in which—

15 Figure 1 is a side elevation of my gin in the extended position. Fig. 2 is a plan view of same. Fig. 3 is a plan view of the gin when it is in condition for transport. Fig. 4 is a 20 side elevation of my device in position for service, the gin being guyed to hold it in a substantially vertical position. Fig. 5 is a modified view of my device.

25 The object of my invention is to provide a convenient, efficient, light, portable gin, especially adapted for work around oil-wells, for pulling and replacing rods, tubing, etc., and which is also well adapted for service in any place where a gin is required or may be employed.

30 The construction of my device is substantially as follows:—

I construct a frame which consists preferably of four pieces of pipe 1, 1, 1, 1, the two 35 pieces of said frame which are vertically related being placed in close proximity to each other, and the top and bottom pieces, in their horizontal relation, being placed at some distance from each other. At one end, the 40 frame pieces 1, 1, 1, 1 are joined by a base 2. At the opposite end, the sides of the frame converge and are firmly held together by means of the strap or collar 3, and at the 45 point where said convergence begins, is located a guide 4 which is rigidly attached to the frame pieces. At the center of both the collar 3 and guide 4, an opening is provided, in which an extension or mast 5 is mounted so as to be slidable longitudinally. At the 50 other extremity of said mast 5 is mounted a crown sheave or pulley 5'.

The particularly novel feature of my device is the construction of the winch and the convertibility of same into wheels, by which 55 the portability of the device is effected, so that it may be readily transported from one

location to another, where it is to be used. The construction of said winch is substantially as follows:—A shaft 6 is revolubly mounted in the bearings 7, and a drum 8, having the respective steps 9, 10, 11, 12 is rigidly mounted upon said shaft 6, which forms the axis of said drum. At each end of the drum is mounted a wheel 13, 13, each of which wheel is also rigidly attached to said axial shaft and said drum. Provision is made for passing a brake-band 14 around either of the wheels 13, for a purpose hereinafter more fully set forth. One end of said band 14 is attached to the U-bolt 14', and the other end 70 thereof is attached to the crank shaft 14'', by means of which crank shaft the brake is operated through the medium of lever 23. The bearings 7 are so constructed that the frame may slide longitudinally through the same, 75 and, for the purpose of securing said frame in the respective positions shown in Figs. 1 and 3, the latches 15, 15,—which are mounted upon shaft 6,—are adapted to engage the pins 16, 16 or 17, 17, which are rigidly attached to frame 1.

When my device is in use for pulling rods or any other work to which it may be applied, the mast 5 is extended and locked in said extended position by means of the pin 85 18, and the winch is secured in position near the base,—as shown in Figs. 1 and 2. The device is then raised to nearly a vertical position, shown in Fig. 5, and secured thus by means of the guys 19, 19. The free end of a 90 rope 20, which is wound upon one of the smaller steps of the drum, is then passed over the sheave 5' and brought down and attached to the object to be lifted,—(a sucker rod 21 of an oil well being shown in Fig. 5). Another rope 22 which has been previously wound upon one of the larger steps of the drum in the opposite direction to that in which the hoisting rope 20 is wound. A horse or team of horses is then hitched to the rope 22 and 100 their pull upon said rope 22 causes the drum to turn and wind up the rope 20 and thus raise the thereto attached weight.

The brake band 14, which passes about a wheel 13, is for the purpose of braking the 105 drum and holding the weight which is being raised, at any desired position. Means are preferably provided whereby said band may be applied to either wheel and the brake lever 23 may occupy a position upon either 110 side of the frame, and with equal facility a weight could be lifted at either side of the

device, as the drum and crown sheave 5 are both located upon the center line of the frame, and work may be done with equal facility upon either side of the machine.

5 When my device is taken down to be moved to another location, the upper end of the frame and the mast are let down to the ground,—it being immaterial which side of the frame is up,—the brake band is detached, latch 15 is disengaged from pin 16, the frame is slid back through the bearings until pin 17 approaches said bearings, pin 17 is then engaged by said latch 15, the mast is slid back through the strap 3 and guide 4, 15 and the device then balances longitudinally over the shaft or axle 6. The wheels 13 now serve the purpose of effecting the mobility of the device, mast 5 serves as a tongue, and a double tree may be attached to the frame as 20 shown by dotted lines at 24, and the device is thus completely equipped and adapted for transport or moving about from place to place.

Having thus described my device, what I 25 claim as new and desire to secure by Letters Patent, is:—

1. In a combined gin and transport, a drum, a wheel of equal diameter at either end of said drum, an axial shaft passing through 30 said drum and said wheels, a bearing at either end of said drum, in which said shaft is revolubly mounted, a frame having its respective sides mounted to slide longitudinally in said bearings, means of securing said

frame at various positions of its longitudinal 35 movement, through said bearings, a base at one end of said frame, a brake band attached at one of its ends to said base, passing about one of said wheels and having its other end attached to a manipulating medium, and a 40 mast slidingly mounted in the other end of said frame.

2. In a combined gin and transport, a frame, a winch mounted in said frame and longitudinally movable therein, means of securing said winch at either limit of said longitudinal movement, said winch being adapted to constitute a hoisting mechanism, there being wheels upon said winch, adapted to travel upon the ground, as and for the purpose set forth. 45

3. In a combined gin and transport, a winch, bearings therefor, a frame mounted in said bearings, and constructed to slide longitudinally therethrough. 55

4. In a combined gin and transport, a frame, a base at one end thereof, a mast slidingly mounted at the other end of said frame, a winch mounted in said frame and adapted to move longitudinally thereof, and means of securing said winch at various points of said longitudinal movement. 60

In testimony whereof I affix my signature in presence of two witnesses.

HENRY F. JAMES.
